UNITED STATES PATENT OFFICE.

JOHN ERTEL, OF NEWBERRY, PENNSYLVANIA, ASSIGNOR TO ARMOUR LEATHER COMPANY, OF CHICAGO, ILLINOIS, A CORPORATION OF ILLINOIS.

STAMPING DEVICE.

Application filed July 22, 1922. Serial No. 576,676.

To all whom it may concern:

Be it known that I, JOHN ERTEL, a citizen of the United States, residing at Newberry, in the county of Lycoming and State of Pennsylvania, have invented certain new and useful Improvements in Stamping Devices, of which the following is a specification.

The present invention relates in general 10 to cutting machines adapted to operate on sheet material such as leather and the like, and is particularly concerned with the provision of a stamping attachment for use in conjunction with machines of the above 15 mentioned character.

The main and primary object of the invention, more specifically stated, resides in 20 the provision of a novel stamping attachment which may be connected, for instance, to a block-sole cutting machine and operated in synchronism therewith to form an impression of a trade, grade or size mark as desired on each block-sole as it is separated 25 from the strip of sole leather passing through the machine.

While the foregoing statement is indicative, in general, of the nature of the invention, other objects and advantages not 30 herein specifically referred to will be appreciated upon a full comprehension of the novel features presented in the construction, arrangement and manner of employment of the present stamping attachment.

In order that the invention may be readily 35 understood an exemplifying embodiment of the same is set forth in conjunction with one particular type of cutting machine in the accompanying drawings and in the following detailed description based thereon. Obviously the invention is susceptible of embodiment in other and varied constructional forms and with other types of 45 associated machines without departure from the essence of the invention or the sacrifice of its material advantages; wherefore it is to be understood that the drawings and description are to be taken in an illustrative 50 and not in an unnecessarily limiting sense.

In the drawings,

Fig. 1 is a fragmentary side elevation of a block-sole cutting machine equipped with

two of the stamping attachments of this invention; 55

Fig. 2 is a fragmentary plan view of the same;

Fig. 3 is a side elevation of the stamping attachment;

Fig. 4 is a longitudinal section on the 60 line 4—4 of Fig. 3;

Fig. 5 is a detail side elevation of one form of the die stem;

Fig. 6 is a detail bottom view of the die 65 head; and

Fig. 7 shows the way in which a strip of sole leather, while being cut, is operated on by the stamping attachments associated with the cutting machine. 70

Referring now to the drawings, and particularly to Figs. 1 and 2 thereof, it will be observed that the stamping attachment which forms the subject matter of this invention is illustrated in one of its typical uses, namely, as operatively associated with 75 a block-sole cutting machine of well known general construction; one of the stamping attachments 10 being connected to each of the two U-shaped cutter-supporting yokes 11 of the machine. The two yokes 11 are pivotally mounted at their extremities to the frame 12 of the machine, and their central cross-beams 13 are alternatively oscillated 80 towards a common cutting bed 14 disposed on the top of the machine frame intermediate the pivoting axes of the yokes. The cutting means supported by the yokes consist of two curved cutters 15 which are adjustably secured to the yoke cross-beams by 85 a plurality of bolts 16 or other suitable means. When the yokes are operated, as in the manner described, the cutters are alternately brought into engagement with the cutting bed and the strip of sheet material being fed through the machine is consequently severed into alternate right and left block-soles, as illustrated in Fig. 7. 90

The stamping attachments 10 are connected to the sides of the yoke cross-beams adjacent the cutters, and operate on the upper surface of the material in synchronism with the operation of the cutters. Each of the attachments 10 preferably consists of a tubular supporting bracket 17, a die stem 18 telescoped within the lower portion of the bracket and movable longitudinally thereof, 100

a die head 19 connected to the lower extremity of the die stem and presenting on its bottom surface the desired mark, a bearing sleeve 20 interposed between the die stem 5 and the bracket, an elongated screw plug 21 adjustably positioned by means of a turning handle 22 in the upper screw-threaded portion of the bracket, a lock nut 23 threaded on the plug and bearing against the upper 10 end of the bracket, a coil spring 24 compressed between the plug and the top of the die stem in the bore of the bracket, and a screw 25 threaded within a transverse aperture in the die stem with its head 26 projecting from the side of the stem into a longitudinally extending slot in one side of the bracket. The slot 27 is provided near its top with a diverging lateral extension which forms an abrupt shoulder 28 on which the 15 head 26 of the screw may be hooked when the die stem and die are moved longitudinally of the bracket into an inoperative position relative to the material on the cutting bed of the machine. It will be understood 20 from this construction that the attachment may be rendered inoperative at will without in any way disturbing the tension on the spring controlling the amount of pressure applied in forming the mark on the material. The bracket 17 is preferably secured 25 to the yoke cross-beam of the machine by means of oppositely disposed flanges 29 which are formed with longitudinally elongated apertures 30 for the reception of bolts 31 carried by the cross-beam, whereby the 30 position of the bracket on the cross-beam may be adjusted longitudinally of the cutter. The die stem may be either straight or offset at its lower end, as shown in Figs. 4 35 and 5, in order that the impression may be made on the material at the desired distance from the curved line of cut regardless of the amount of offset in the cutter due to its curvature at the particular point opposite 40 the stamping attachment.

In operation the stamping attachments move alternately with the cutters toward and away from the material on the cutting bed of the machine, the brackets of the attachments being secured to the yoke cross-beams in such positions that the bottoms of the die heads are substantially flush with the bottom edges of the cutters while both are in their elevated positions prior to the actual cutting and stamping operations. As each cutter descends and cuts through the strip of material on the cutting bed its associated stamping die comes into contact with the upper surface of the material and imprints 55 the mark thereon, the depth of the impression thus made being regulated by the pressure exerted on the spring 24 by the readily adjustable screw plug 21. If it is desired to throw the stamping attachments out of operation it is only necessary to press the die 60

stems upwardly in their brackets and then turn them laterally a sufficient distance to effect a locking engagement of the screw heads 26 with the shoulders 28 in the slots of the brackets.

70

I claim:

1. In a cutting machine, a support for the material, a cutter movable toward and away from the support, and a stamping die movable with the cutter and shiftable at will 75 relative thereto into an inoperative position.

2. In a cutting machine, a support for the material, a cutter movable toward and away from the support, a stamping die movable with the cutter, yielding means for positioning the die relative to the cutter, and means for adjusting said yieldable means 80 during the operation of the machine.

3. In a cutting machine, a support for the material, a cutter movable toward and away 85 from the support, a stamping die movable with the cutter, adjustably yieldable means for positioning the die relative to the cutter, and means for shifting at will the die relative to the cutter into an inoperative position without disturbing the adjustment of the yieldable means.

4. A stamping attachment of the character described comprising a tubular mounting bracket, a die having a stem portion reciprocally mounted within the bracket, an abutment adjustably positioned longitudinally of the bracket, and a spring disposed between the abutment and the stem for resisting movement of the die toward the 90 abutment.

5. A stamping attachment of the character described comprising a tubular mounting bracket, a die having a stem portion reciprocally mounted within the bracket, an abutment adjustably positioned longitudinally of the bracket, a spring disposed between the abutment and the stem for resisting movement of the die toward the abutment, and a projection extending from one 100 side of the stem through a slot in the bracket for preventing angular movement between the die and the bracket.

6. A stamping attachment of the character described comprising a tubular mounting bracket, a die having a stem portion reciprocally mounted within the bracket, an abutment adjustably positioned longitudinally of the bracket, a spring disposed between the abutment and the stem for resisting movement of the die toward the abutment, and a projection extending from one side of the stem through a slot in the bracket for preventing angular movement between the die and the bracket said slot being provided with an offset portion adapted to receive the projection and hold the die in an inoperative position.

7. In a cutting machine, a support for the material, a cutter movable into and out of 130

contact with the support, and a stamping die movable with the cutter, said die being also movable relative to the cutter in a direction at right angles to the support when 5 the cutter is in its cutting position in contact with the support.

8. In a cutting machine, a support for the material, a cutter movable into and out of contact with the support, and a stamping die movable with the cutter, said die being also movable relative to the cutter in a 10 direction parallel to the axis of the same when in its cutting position in contact with the support.

15 9. A stamping attachment of the char-

acter described comprising a mounting bracket adapted for movement toward and away from the material to be stamped, in unison with the major mechanism on which the attachment is intended to be mounted, a 20 die associated with the bracket, and means for yieldingly resisting movement of the die longitudinally of the bracket upon continued movement of the bracket toward the material after the die has contacted with the 25 material.

In testimony whereof I have hereunto subscribed my name.

JOHN ERTEL.
